Primary Examiner—M. H. Tung

[57] CLAIM

The ornamental design for a hinge for a portable computing device, as shown and described.

DESCRIPTION

FIG. 1 is a rear elevational view of a hinge for a portable computing device showing my new design; and,

FIG. 2 is a top plan view thereof. The broken line drawing of a portable computing device in both views is shown for illustrative purposes only and forms no part of the claimed design.
